CLAIM

I claim the ornamental design for the filter element, as shown and described.

DESCRIPTION

FIG. 1 is a perspective view of the filter element showing my new design;
FIG. 2 is a side view of the filter element of FIG. 1;
FIG. 3 is a side view of the filter element of FIG. 1 showing the side opposite that shown in FIG. 2;
FIG. 4 is a back view of the filter element of FIG. 1;
FIG. 5 is a front view of the filter element of FIG. 1;
FIG. 6 is a top view of the filter element of FIG. 1; and,
FIG. 7 is a bottom view of the filter element of FIG. 1.

1 Claim, 6 Drawing Sheets
